CENTERING MEANS FOR CATHODE-RAY
DEFLECTING CIRCUITS

Paul F. G. Holst and Loren Robert Kirkwood,
Oaklyn, N. J., assignors to Radio Corporation
of America, a corporation of Delaware

Application October 28, 1944, Serial No. 560,756

2 Claims. (Cl. 315—31)

1

The present invention relates to cathode ray tube circuits, and more particularly to a novel centering means for placing the trace in the desired location on a cathode ray indicator or image producing tube or the like.

The principal object of the present invention is to provide a novel and suitable centering means which maintains optimum focusing of the cathode ray tube over the entire range of adjustment provided by the circuit.

Another object of the invention is to produce a novel and reliable source of centering voltages which is of the balanced push-pull type, which maintains the best focus conditions regardless of the setting of the centering control, and which permits the operator to displace the trace to both sides of its center position.

Still another object of the invention is to provide a simple and efficient balanced push-pull centering means, which can be produced from standard, commercially available, component parts.

Other objects and advantages of the invention will, of course, become apparent and immediately suggest themselves to those skilled in the art to which the invention is directed from a reading of the following specification in connection with the accompanying drawing which shows, illustratively and schematically, a cathode ray indicator circuit embodying the invention.

Referring to the drawing, a cathode ray tube 10 of any well known type is shown as being connected to external circuits in such a manner that separate alternating deflection voltages applied to deflection voltage input connections or terminals 12 and 14 will produce a trace or pattern on the fluorescent screen 16 of the tube.

Electrostatic deflection plates 17 and 18 deflect the electron beam 19 developed within the tube in one plane, while electrostatic deflection plates 21 and 22 deflect the beam in a plane at right angles to the direction controlled by the plates 17 and 18. The resultant deflection of the beam, as the voltages applied to the input connections 12 and 14 vary, causes the beam as it impacts upon a target area, such as the usual fluorescent or luminescent screen 16, to trace a distinctive visual raster or pattern. The electron beam is produced in a well-known manner by an electron gun comprising an electron source in the form of an indirectly heated cathode 24, a control electrode or grid 26, and an electrode 27 which functions as an accelerating electrode. This electrode is usually referred to as the second anode and in some instances is in the form of a cylinder or of a coating on the envelope

2

or wall of the tube. The resulting luminous spot on the cathode ray screen 16 can, in known manner, be regulated as to size and intensity by suitable choice of electrode voltages. An additional anode 28, normally referred to as the first anode, cooperates with the anode 27, varying the spot size and intensity. These tube electrodes are all of usual and known construction. To this end, the electrode 28 may be connected to a variable potential source in known manner which may be adjusted to the correct value with respect to that applied to the electrode 27. The voltage applied to the second anode 27 and its relationship to the centering voltages for a pair of deflecting plates, for example plates 17 and 18, will be discussed more in detail hereinafter as it constitutes a part of the present invention. Likewise, the control grid 26 is connected in known manner to a potential source which is negative with respect to the cathode and is preferably made adjustable.

Suitable direct current sources, for example rectifiers, are connected to terminals 29, 31, and 32. Suitable voltages may be obtained from the sections 33, 34, 65, 66, 67, and 68 of bleeder resistor circuits connected between the terminals 29, 31, and 32. The negative terminal 31 may be grounded or with slight circuit modifications, which are well known to those skilled in the art, the positive terminal 32 or some intermediate potential as shown may be grounded so as to place the cathode 24 and the heater 36 at a high negative potential with respect to ground whereby conducting portions in the apparatus presenting dangerous voltage can more easily be made inaccessible.

Cathode potential is provided at the junction of 67 and 68, while a variable D. C. voltage, negative with respect to the cathode 24, for the grid 26 is provided at the movable arm of 68. The anode 28 is also provided with a variable potential positive with respect to the cathode from the arm of 66. These variable voltages are supplied to the cathode ray tube at the terminals 39 and 40, respectively. Focusing of the fluorescent spot produced by the beam 19 is controlled in the usual manner by adjustment of the ratio of the voltage on anode 27 to the voltage on the anode 28. This may be done conveniently by varying the magnitude of the voltage applied to the terminal 40.

Regulation of the spot size and spot intensity can be accomplished by varying the current to or voltage on the anode 27. The current to the anode 27 may be increased by decreasing the bias voltage applied to the grid 26. An increase in the anode current of the anode 27 increases the size

and intensity of the spot. An increase in the voltage applied to the anode 27 increases the speed of the electrons which increases the spot intensity and may decrease the spot size. It will be understood, therefore, that the grid 26 may be reserved for modulating the beam 19 if the tube 10 is to be used for production of television images or the like.

The deflecting voltages applied to the previously mentioned sets of terminals 12 and 14 may be amplified or otherwise modified, if desirable or necessary, in circuits 42 and 43. The circuits 42 and 43 may also include deflection generators, such as oscillators for producing a desired wave form, or other deflection circuits. The connections 12 and 14 may then be omitted or used only to apply control pulses. The deflecting plates 17 and 18 are connected to the output of the amplifier 42, if desired, through coupling condensers 46 and 47. Likewise, the plates 21 and 22 are connected to the output of the circuit 43 by condensers 48 and 49. It will be understood that each of the circuits 42 or 43 may comprise any suitable or special coupling network or mesh which is to be interposed between the terminals 12 and the plates 17 and 18, or the terminals 14 and the plates 21 and 22. In the arrangement shown for the purpose of illustrating the invention, the circuits 42 and 43 may be of the balanced push-pull type although one or both may be unbalanced or single ended, if desired.

The deflecting plates 21 and 22 are connected in push-pull to the circuit 43 through coupling capacitors 48 and 49, while centering voltages are supplied from a push-pull source of centering voltages. This network comprises resistors 55, 56, and 69 and the potentiometer 52. The resistors 55 and 56 are each connected at one end to the supply terminal 32, and the free ends are connected to the ends of the potentiometer resistor 52. The adjustable contact 72 of the potentiometer 52 is connected through a resistor 69 to the terminal 29 of the power supply. The plate 21 is connected to the junction of the resistor 55 and the potentiometer resistor 52 through the resistor 53, and the plate 22 is connected to the junction of the resistor 56 and the potentiometer resistor 52 through the resistor 51. The resistors 55 and 56 and the resistor element of the potentiometer 52 are preferably substantially equal in value. Solely by way of example, the two resistors 55 and 56 and the potentiometer resistor 52 may have a value of one megohm each. With these illustrative values, the resistor 69 will have a value of approximately 270,000 ohms.

The circuit 43 is labeled as a vertical deflection circuit and therefore the plates 21 and 22 serve as the vertical deflecting plates for the tube 19.

With the arm 72 of the potentiometer 52 at the midpoint of the potentiometer resistor 52, the voltage on each plate 21 and 22 will be equal and have a value approximately equal to one-half of the value of the voltage applied across the terminals 32 and 29. When the arm 72 of the potentiometer 52 is turned until it is connected to the junction of the resistor 56 for example, the voltage on the plate 22 will be $2\frac{1}{3}$ of the voltage applied across the terminals 32 and 29, while the voltage on the plate 21 will be $6\frac{2}{3}$ of this total voltage. The average of these voltages applied to the plates is approximately equal to one-half of the voltage applied across the terminals 29 and 32 with the potentiometer arm 72 in its center position. With the voltages reversed by turning the

potentiometer arm 72 so that it is effectively in contact with the lead from the plate 21, the trace is moved the same amount in the other direction. The circuit, therefore, produces centering voltages which may be varied to move the beam about the center in either direction and to have an average voltage which is approximately equal to half the voltage between terminals 32 and 29. Best focusing conditions are produced if the average of the centering voltages equals the second anode voltage. Using the centering circuit disclosed, this condition will be realized, irrespective of the position of the centering voltage control if the second anode bleeder, comprising the resistors 33 and 34, is so designed that the voltage on the second anode 27 is equal to one-half of the voltage impressed across the terminals 32 and 29. The point of connection 74 to the bleeder circuit is selected so that the voltage on the second anode 27 is equal to one-half of the voltage applied across the terminals 32 and 29 which, as stated, is the average voltage on the deflection plates 21 and 22.

The amplifier 42 is labeled as a horizontal sweep amplifier by way of example, and therefore plates 17 and 18 serve for what are normally known as horizontal deflecting plates whether the invention is applied to an oscilloscope, as stated above, or to an image producing tube of a television system or the like. The centering voltage for the plates 17 and 18 may be obtained as shown by way of example from a centering circuit 71, 60, 61, 62, 63, and 64. The centering voltage for the plates 17 and 18 may also be obtained in the manner disclosed and claimed in the application of the present inventors, Serial No. 560,755, entitled "Centering means for cathode ray deflecting circuits," filed concurrently herewith.

Various modifications of the invention shown and described herein by way of example are possible without departing from the spirit and scope of the invention described herein, and it is desired that any and all of such modifications be considered within the purview of the present invention defined by the hereinafter appended claims.

Having now described the invention, what is claimed and desired to be secured by Letters Patent is the following:

1. An arrangement for providing centering voltages for the deflecting plates of a cathode ray tube having means for generating a cathode ray beam and an accelerating electrode comprising a resistor combination having a pair of resistors one end of each resistor being connected to a third resistor, the other ends of said pair of resistors being joined together, said plates being connected to the ends of said third resistor, a variable contact in engagement with said third resistor, a fourth resistor connected to said variable contact, and terminal means to provide for impressing a voltage across said resistor combination from the free end of said fourth resistor to the ends of said pair of resistors, and means to supply a relatively fixed voltage to said accelerating electrode substantially equal to the average of the voltages applied to said plates.

2. Apparatus comprising an electrostatically focused cathode ray tube, said tube having a first anode, a second anode, and cooperating deflection plates, means for supplying a voltage to said first anode, and means for supplying centering voltages to said deflection plates, said last named means comprising a potentiometer having a resistor and an adjustable contact, a pair of resist-

ors connected to each end of said potentiometer resistor, each plate also being connected to an end of said potentiometer resistor, a resistor in series with said adjustable contact, and means for supplying a relatively fixed voltage to said second anode substantially equal to the average of the voltages supplied to said plates.
